UNITED STATES PATENT OFFICE.

ARTHUR C. PAYSON, OF MILAN, ILLINOIS.

VALVE-SURFACING DEVICE.

1,409,764.

Specification of Letters Patent. Patented Mar. 14, 1922.

Application filed June 12, 1920. Serial No. 388,447.

To all whom it may concern:

Be it known that I, ARTHUR C. PAYSON, a citizen of United States, residing at Milan, in the county of Rock Island and State of Illinois, have invented a certain new and useful Improvement in Valve-Surfacing Devices, of which the following is a full, clear, concise, and exact description, reference being had to the accompanying drawings, 10 forming a part of this specification.

This invention relates to improvements in valve surfacing devices.

One object of this invention is to provide a device for easily, quickly and accurately 15 re-surfacing or dressing down valves, such as are commonly employed in internal combustion motors used on automobiles.

Another object of the invention is to provide a relatively inexpensive device of the 20 character indicated which may be set up in a vice or otherwise clamped and wherein the surface of the valve is trued or turned always accurately with respect to the usual valve stem.

25 Other objects of the invention will more clearly appear from the description hereinafter following.

In the drawings forming a part of this specification, Figure 1 is a side elevation of a 30 device embodying my invention, the same showing a valve in position to be dressed down or resurfaced. Figure 2 is a vertical central longitudinal section of the structure illustrated in Figure 1 and corresponding substantially to the line 2—2 of Figure 3. Figure 3 is an elevational view of one end of the device shown in Figure 1. Figure 4 is a vertical sectional view corresponding substantially to the line 4—4 of Figure 1. Figure 5 is a detail sectional view taken substantially on the line 5—5 of Figure 2. And Figure 6 is an end view of a collet employed 40 in my improvements.

In said drawings, 10 denotes a suitable 45 base or frame upon which the other parts of the device are mounted as hereinafter described. Said frame 10 is preferably in the form of a light casting and is provided with a flat bottom 11 and vertical side walls near 50 the bottom as indicated at 12—12 so that the device may be easily clamped in a vice. To save metal and promote lightness, the frame 10 may be centrally cored as indicated at 13.

In carrying out my invention, I provide 55 means for rotatably supporting a valve and its stem, the valve proper being indicated at

14 and its stem at 15. Said means preferably comprise a sleeve or bushing 16 rotatably mounted within a suitable opening 17 formed in the frame 10, said bushing 16 having a collar 18 at one end thereof countersunk within the frame 10 and exteriorly threaded at its opposite end as indicated at 19 and upon which are adapted to be screwed two lock washers 20—20. A brass or other 60 suitable friction-reducing metal disc 21 is countersunk into the frame so as to minimize the resistance to the rotation of the sleeve or bushing 16. The bushing 16 is open from end to end and receives therein a collet 22. 70 The collet is slotted into sections 22^a, 22^b and 22^c, as shown in Figure 6, at its holding or clamping end and said sections are tapered as indicated at 23 so as to cooperate with a correspondingly tapered mouth 24 75 formed at the end of the bushing 16. The opposite end of the collet is exteriorly threaded and receives a manually adjustable knurled nut 25. By screwing the nut 25 up on the collet, it is evident that the latter will 80 be drawn so as to securely clamp the stem 15 of the valve. To prevent the collet from turning with respect to the bushing, the latter may have a pin 26 on the interior 85 thereof with which cooperates a longitudinally extending slot 27 formed in the collet.

In actual practice, the opening within the collet will be made to accurately fit standard sizes of valve stems, different collets being employed for different sizes. With this construction, it is evident that the valve stems must be straight, otherwise they cannot be properly clamped and hence I avoid wasted time and energy in re-surfacing valves that have bent or distorted stems that cannot be 90 used even though the valve surface is re-finished.

As is well known, the active surfaces of the valves of standard construction extend at a definite angle with respect to the axis 100 of the stem, this angle being 45°. Taking advantage of this fact, I provide a cross head 28 which is slidably mounted in guideways 29—29 that extend at the same angle, 45°, with respect to the axis of the valve 105 stem, as clearly indicated in Figure 2. The guideways 29 are provided with removable suitably rabbeted plates 30—30 bolted to the frame 10 as shown in Figure 3. The cross head 28 carries a nut 31 with which cooperates a feed screw 32 as shown in Figure 2. The lower end of the feed screw is jour- 110

naled in the frame 10 as indicated at 33 and at its upper end passes through an opening in a plate 34 screwed or bolted to the frame 10. Beyond the plate 34 the feed screw has secured thereto a bevel gear 35 and also a knurled sleeve 36, the latter and the bevel gear being pinned or otherwise rigidly secured to the feed screw. As will be evident, rotation of the feed screw 32 shifts the cross head 28 either up or down at an angle of 45° with respect to the axis of the valve stem when the latter is held by the collet.

The cross head 28 is provided on its under side with an undercut horizontally extending guideway 37 in which is slidably mounted a cutting tool 38. Connected by a swivel joint indicated at 39 is a horizontally extending adjusting screw 40 which is threaded in a depending flange 41 formed on the cross head 28. The outer end of the adjusting screw 40 carries a rigid knurled nut 42. A small cutting tool 43 is carried by the tool holder 38, said cutting tool 43 being secured in place by any suitable means such as the stud bolt 44 indicated most clearly in Figure 5. As will be evident from an inspection of Figures 2 and 3, the cutting tool 43 is so arranged that the cutting edge is presented to the surface of the valve and will turn down the latter in the manner of the ordinary cutting tool employed on a lathe.

In order to effect the movements of the cross head 28 and rotation of the valve in synchronism, I employ the following construction. The bushing 16 carries a gear 45 with which meshes a pinion 46 loosely mounted on a stud bolt 47 carried by the frame 10. The pinion 46 meshes with a larger gear 48 which is loosely rotatably mounted on a second stud bolt 49. The gear 48 carries a pair of diametrically opposed set screws 50, each of which carries a bushing 51, the outer ends of the set screws 50 securing a lever 52 in place, the latter having an operating handle, a part of which is indicated at 53 in Figure 1. As will be evident, the operator rotates the lever 52 which causes rotation of the gears and pinions 48, 46 and 45, thereby effecting rotation of the valve and its stem.

Rigid with the gear 48 is a smaller gear 54 which meshes with a gear 55 splined to a horizontally extending shaft 56 mounted in suitable bearings formed in upstanding projections 57 of the frame 10. Washers 58-58 are pinned to the shaft 56 so as to prevent longitudinal movement thereof as clearly shown in Figure 2. The end of the shaft 56 remote from the gear 55 is formed with a bevel or spur gear 59 which cooperates with the bevel gear 35, the ratio of the gears 59 and 35 being substantially one to four. The ratio of the gears 48 and 54 is substantially four to one and of the gears 54 and 55, sub-

stantially one to two. The ratio of the 65 gears 48 and 45 is substantially two to one.

With the construction described, it is evident that the cross head 28 will be fed very slowly but always in synchronism with the rotation of the valve 14. The cutting tool 70 43 will be shifted across the face of the valve always in a line at 45° to the axis of the valve stem and the depth of the cut on the valve surface is adjusted by means of the screw 40. For convenience in re-setting the cross head 28 more quickly than is possible by means of rotating the lever 52, I slip the gear 55 out of mesh with the pinion 54 and then rotate the screw 32 in a reverse direction by means of the knob 36. 80

With my improvements, it is evident that I obtain a true surface on the valves and one which is independent of any special skill on the part of the operator and furthermore, the speed with which the valves can be 85 dressed is very much greater than that which now obtains under the so-called grinding process and which are more or less inaccurate. The cutting made by the tool 43 may be made comparatively shallow or comparatively deep dependent upon the condition of the valve and substantially no more time is required to re-surface a badly worn or pitted valve than in the case of one which is only slightly worn. As heretofore explained the use of the collet in holding the valve stem will automatically cause the rejection of any valves having the stem so deformed as to prevent their further use regardless of the condition of the valve itself. 90 The cost of manufacture of the device is comparatively small; the same is readily portable and it may be used in many shops which are not now equipped to grind valves, thereby filling a long felt want. 95

Although I have herein shown and described what I now consider the preferred manner of carrying out the invention, the same is merely illustrative and I contemplate all changes and modifications that 100 come within the scope of the claims appended hereto.

I claim:

1. In a device of the character described, the combination with a suitable frame; of 115 means mounted on the frame for rotatably supporting a valve having a stem and including a collet for the stem; a cross head mounted to slide on the frame parallel to the true angle of the valve surface; means 120 for advancing said cross head; a tool holder mounted on the cross head; and commonly operated, trains of gears for continuously and simultaneously rotating the valve and stem-supporting means and the cross head 125 advancing means.

2. In a device of the character described, the combination with a suitable frame; of

means mounted on the frame for rotatably supporting a valve having a stem; a cross head slidably mounted on the frame to move in a direction parallel to the true angle of the valve surface; a tool holder mounted on said cross head; a manually adjustable screw for shifting said tool holder on the cross head in a direction parallel to the axis of the valve and its stem; means for rotating the valve supporting means including a train of gears; and means, including a shaft, meshing gears and a screw, for moving said cross head.

3. In a device of the character described, the combination with a frame; of means mounted on the frame for rotatably supporting a valve having a stem; a cross head mounted to slide on the frame in a direction parallel to the true angle of the valve surface; a feed screw cooperable with said cross head to advance and retract the same; a tool holder carried by the cross head; manually operable gearing for effecting simultaneous rotation of the feed screw and said means, said gearing including a splined gear readily disengaged from an adjacent cooperating gear; and independent manually operable means for rotating said feed screw when said splined gear is so disengaged.

30 4. In a device of the character described, the combination with a frame; of means

mounted on the frame for rotatably supporting a valve; a cross head slidably mounted on the frame to move in a direction parallel to the true surface of the valve; a tool holder slidably mounted on the cross head to move in a direction parallel to the axis of the valve; manually adjustable means for advancing or retracting the position of the tool holder axially with respect to the valve; means for advancing or retracting the cross head; and means for effecting rotation of the valve supporting means.

5. In a device of the character described, the combination with a frame; of a valve stem-holding collet rotatably mounted in the frame; a cross head slidably mounted on the frame at an angle of 45° to the axis of the collet and adjacent one end of the latter; a tool holder adjustably slidably mounted on the cross head in a direction parallel to the axis of the collet; a feed screw for effecting movement of the cross head; and common manually operated gearing for effecting continuous rotation of the feed screw and the collet in synchronism.

In witness that I claim the foregoing I have hereunto subscribed my name.

ARTHUR C. PAYSON.
